UNITED STATES PATENT OFFICE.

RALPH TH. CORDEAU, OF NEW YORK, N. Y., ASSIGNOR TO GLEASON-TIEBOUT GLASS COMPANY, OF BROOKLYN, NEW YORK, A CORPORATION OF NEW YORK.

DESIGN FOR A GLASS SHADE OR BALL.

No. 39,182.

Specification for Design.

Patented March 10, 1908.

Application filed January 21, 1908. Serial No. 412,019. Term of patent 7 years.

To all whom it may concern:

Be it known that I, RALPH TH. CORDEAU, a citizen of the United States, and a resident of Flushing, in the borough of Queens, city of New York, county of Queens, and State of New York, have invented a new, original, and ornamental Design for Glass Shades or Balls, of which the following is a specification, reference being had to the accompanying drawing, forming part thereof.

The figure represents a perspective view showing my new design.

I claim

The ornamental design for a glass shade or ball, as shown.

RALPH TH. CORDEAU.
